UNITED STATES PATENT OFFICE.

JOHN STEWART, OF NEWARK, NEW JERSEY.

PRESS.

SPECIFICATION forming part of Letters Patent No. 334,485, dated January 19, 1886.

Application filed November 23, 1885. Serial No. 183,675. (No model.)

To all whom it may concern:

Be it known that I, JOHN STEWART, a citizen of the United States, residing in the city of Newark, county of Essex, and State of New Jersey, have invented certain new and useful Improvements in Presses, of which the following is a specification.

My improvements relate to the class of presses known as "toggle-presses," in which the flexion of the toggle-levers is effected by means of a nut or nuts which travel upon a rotating screw-shaft. Two of these toggle-joints are usually incorporated in a single press, being opposed to each other in position and actuated by a single screw-shaft formed with opposed or right and left screw-threads, which respectively engage with suitable nuts which support the central or knee knuckles directly.

This class of toggle-press, while applicable to a large variety of uses, is desirable where great pressure is required, particularly where the maximum degree of pressure is required to be exerted at or near the completion of the stroke, since it is obvious that in proportion as the toggle-levers advance or straighten out the pressure exerted by the platen will be gradually augmented while its motion will decrease correspondingly. The toggle-press is thus desirable where heavy pressures are to be applied intermittently and rapidly; but heretofore the strength and capacity of the apparatus have been limited and its construction rendered complicated and expensive from the fact that the actuating screw-shaft has always been mounted so that it could follow with and adapt itself to the varying positions of the toggle-levers. In other words, the knee-knuckles have always been rigidly attached to or formed a part of the actuating-nuts, and since the lower or ankle joints of the toggles were necessarily stationary in position the actuating-shaft, in order to render the device operative at all, had necessarily to rise and fall with and to the same extent as the platen. The mechanical inconvenience of applying power to such a shaft is obvious. It will thus readily be seen that the lateral movement of the power-shaft is a disadvantage in a power-press of this character, where the most essential requisites are strength and durability

combined with simplicity of construction and operation.

By my invention I obviate these objectionable features and am enabled to produce a powerful and durable apparatus in a simple and compact form; and the main feature of my invention consists, essentially, in incorporating a third member or members into each toggle-joint, constituting in each case a link or links between the main or knee knuckle of each toggle and its actuating-nut. By this means I am enabled to mount my power-shaft so that it is stationary in position while free to revolve between fixed bearings, since the third lever or connecting-link, by its freedom to adapt itself to the changes in the vertical position of the knee-knuckles, will impart motion thereto in all respects like the old form of direct actuating-nut without any of its attending disadvantages.

Another feature in my invention relates to the special means of counteracting the lateral twist or strain exerted upon the nuts by the actuating-screw while in operation; and it consists in forming the nuts with lateral extensions, preferably provided with anti-friction rollers, which rest between longitudinal shoulders or supports formed upon or attached to a stationary part of the apparatus. This feature, though not absolutely indispensable, is of importance in connection with my form of press, since it helps to insure the proper alignment and operation of my supplementary actuating levers or links.

An incidental feature of my invention consists in making the anvil in the form of an adjustable screw, and in combining with it an index for the purpose of regulating the position of the pressure or resisting surface with relation to the stroke of the platen with accuracy. In the more delicate classes of work—as in die work—this accurate and delicate adjustment of the anvil is of importance.

My invention also includes the special forms of construction hereinafter described.

It is to be understood that I do not limit myself strictly to the special form of press shown in the accompanying drawings, such form being shown merely as a means of illustrating the practical embodiment and operation of my improvements, which are applica-

ble to presses of various forms and uses. For instance, it is immaterial, as far as the invention is concerned, whether one or two toggles are used, or whether one or two supplemental levers or links are used in connection with each actuating-nut.

The apparatus may also be arranged to operate horizontally or at any intervening angle, if desirable, and the form of the anvil or resisting-surface, as well as of the means for counteracting the lateral strain upon the nut, may be modified to suit other circumstances and conditions.

With this explanation it may be stated that the press represented in the drawings is designed more especially for the compression of metals, &c., between suitable dies to be interposed between the upper surface of the vertically-moving platen and the lower resisting-surface of the adjustable screw or anvil.

In the accompanying drawings, Figure 1 is what may be designated as a "front" elevation of a power-press embodying my improvements, showing the toggles extended; Fig. 2, a sectional plan of same upon plane of line $x-x$, Fig. 1; Fig. 3, a sectional elevation of the apparatus, with the upper portion broken away and the two front columns removed from position to more clearly show the construction of the toggles, one of which, together with its actuating-nut, is shown in section. In both Figs. 2 and 3 the toggles are shown as retracted. Fig. 4 is a vertical sectional elevation taken upon plane of line $y-y$, Fig. 1, the toggles being represented as corresponding in position with the said Fig. 1. Fig. 5 represents isometrical details of one of the actuating-nuts, link, friction-roller, &c., detached.

The apparatus is mounted upon a suitable bed, A, which affords adequate means for securing and supporting the bearings or standards B B' B² in proper relation to each other.

Between and upon the bearings B B' B² is mounted the horizontal shaft C.

Suitable means for applying power to and reversing the shaft C are arranged between the standards B B', that represented in the drawings, S, being my special form of speeding apparatus shown and described in Patent No. 252,537, dated January 17, 1882, which is used in connection with the ordinary mechanism for starting and reversing engine-lathes, &c.

It is to be understood that I do not limit myself to this means of applying power to and reversing the motion of the shaft C, as any other well-known or suitable means may be substituted therefor, such means being independent and forming no part of my present invention.

The portion of the power-shaft C between the bearings B' and B² is formed in about equal proportions with the right and left hand screw-threads c c', which engage with correspondingly-threaded nuts D and D', which are free to travel longitudinally in opposite directions upon their respective portions of the shaft C. The nuts D D' are formed with

laterally-projecting trunnions d d, to which are pivotally connected my supplementary toggle levers or links E. These supplemental toggle levers or links E are preferably formed as shown in the drawings—that is, with the eye or socket e at one extremity for engagement with the trunnions d d upon the nut and at the other extremity with the cylindrical portions or trunnions e', which constitute the knuckles for the central or knee joint formed by and between the hip-levers F F and ankle-levers F' F', which combined constitute the toggles TT. The lower or ankle toggle levers, F' F', are pivotally connected to the stationary bed A', projecting upward from the bed-plate A, while the upper or hip toggle-levers, F F, are similarly pivotally connected with the vertically-moving platen H. The form of these pivotal connections may be varied and modified as desired without affecting the novel use of the supplemental levers or links E E and other features of my invention; but I prefer to construct them as follows, to wit:

In the under side of the platen H, I form semicircular seats h h, and in the upper side of the stationary bed A' similar semicircular seats, a a, into which fit loose cylindrical trunnions t t'. The upper ends of the hip-levers F and the lower ends of the ankle-levers F' are respectively formed with corresponding seats or recesses, f f', which fit over and engage the loose trunnions t t'. The lower ends of the hip-levers F F and the upper ends of the ankle-levers F' F' are correspondingly formed with seats or grooves f² f³ for engagement with the link-trunnions e' e', the adjoining portions of the ends of the levers F F' being in each case chamfered, as shown at f' f', or otherwise shaped, so as to permit of the free movement of all the levers or arms. The under edges of the hip-levers F and the upper edges of the ankle-levers F' F' are also formed centrally with the recess f⁶ f⁶, (shown in Figs. 2 and 3,) for the purpose of permitting of their free movement without contact with the shaft C. These independent cylindrical trunnions t t', besides facilitating the taking apart or assembling of the apparatus, adapt themselves more readily to the strain imposed, and distribute it more evenly throughout the entire bearing-surface than where the old form of hinge-joint is used, so that there is less friction and wear. The platen H rests upon the upper trunnions t t, and between the columns or uprights I I, which are preferably, though not necessarily, square in cross-section, and four in number, the platen being notched or shouldered, as shown at h' h', to engage the inner edges of the columns I. The latter are preferably made hollow, and firmly secured to the base A by strong stay-bolts J J, passing centrally through them and secured by nuts j j to the cross-head K K, which rests upon the top of the columns I I. This cross-head K, being formed with an interior central female screw-thread, constitutes a stationary nut for the large screw-anvil L, the lower surface, l, of which afford

the necessary resistance to the upward thrust of the platen H. The screw-threads upon the anvil L and in the nut K are preferably large in cross-section and of slight pitch, so as to resist effectually the pressure from below; and the screw-anvil L is provided with a hand-wheel, I', or equivalent device, by which the vertical adjustment of the pressure-surface l may be effected.

10 A stationary index-point, k, projects from a stationary part of the apparatus in proximity to the periphery of the hand-wheel, where the latter is used, and constitutes a means, when compared with the scale upon the periphery 15 of the wheel I', of indicating the downward projection of the resisting-surface l below. Other means may be employed, if preferred, for thus indicating and regulating the position of the resisting-surface l.

20 In order to resist the lateral strain upon the nuts D, and their consequent tendency to revolve with the shaft C, lateral projections n n are formed to project from the nuts D D', in such manner as to engage stationary ways or 25 shoulders o o, formed upon or attached to stationary parts of the apparatus. These lateral projections n n are preferably formed as continuations of the trunnions d d, and they are also preferably provided with anti-friction rollers n' n', which rest in the grooves o' o', formed by and between the opposed stationary shoulders o o, so that no matter what the direction of motion of the shaft C may be the lateral 30 projections n will sustain the nuts in proper alignment, and if the anti-friction rollers n' n' are used will facilitate the movement of the said nuts D D' in either direction. The stationary shoulders o o are of course arranged 35 parallel to the actuating-shaft C.

40 The operation of the apparatus is as follows: The toggles T having been deflected or separated, substantially as shown in Figs. 2 and 3, by causing the shaft C to rotate in the proper direction by the usual means, the male and 45 female dies, with the material to be compressed or shaped between them, are placed upon the platen H and the motion of the shaft C reversed, thereby causing the screws c c' to propel the nuts D D' toward each other. This 50 movement is transferred by the supplemental levers or links E, through the trunnions e e, to the toggle-levers F F', causing them to gradually assume a vertical or nearly vertical position, as shown in Fig. 1, thus compressing 55 the material between the dies placed between the upper surface of the platen H and the under surface of the anvil l. The direction of motion being again changed, the platen is caused to again descend, when the operation, as before set forth, may be repeated.

60 What I claim as my invention, and desire to secure by Letters Patent, is—

1. In a power-press substantially such as designated, the combination, with a stationary rotating shaft formed with a screw-thread and with a toggle-joint, one lever of which is pivotally connected to a stationary part of the

apparatus and the other lever of which is pivotally connected to a movable platen, of a traveling nut engaging the said screw-thread 70 and provided with a supplementary link or lever by which the said nut is pivotally connected with and actuates the said toggle-lever, substantially in the manner and for the purpose described.

2. In a power-press substantially such as designated, the combination, with a stationary rotating shaft formed with a right and left screw-thread and with a pair of toggle-joints, the extremities of which are pivotally connected with a stationary part of the apparatus and the other extremities of which are pivotally connected with a movable platen, of oppositely-moving nuts engaging the said right and left screw-threads formed upon the 80 stationary revolving shaft, said nuts being provided with supplemental levers or links by which the said nuts are pivotally connected with and actuate the said toggle-levers, substantially in the manner and for the purpose 85 described.

3. In a power-press substantially such as designated, the combination, with one or more toggle-joints actuated by a nut or nuts movable upon screw-threads formed upon the 95 power-shaft, of a loose cylindrical trunnion or trunnions seated in a suitable bearing or bearings formed in either or both the movable platen and the stationary bed and in similar concentric bearings in the extremities of the 100 toggle-levers, substantially in the manner and for the purpose described.

4. In a power-press substantially such as designated, the combination, with a rotating shaft formed with one or more screw-threads 105 and with one or more toggle-joints, the levers of which are respectively pivotally connected to a stationary part of the apparatus and to a movable platen, of a traveling nut or nuts formed with one or more lateral projections 110 which engage stationary shoulders which are parallel with the said actuating-shaft, substantially in the manner and for the purpose described.

5. In a power-press substantially such as 115 designated, the combination, with a stationary revolving shaft formed with one or more screw-threads and with one or more toggle-joints, the levers of which are respectively pivotally connected with a stationary part of 120 the apparatus and to a movable platen, of a traveling nut or nuts formed with one or more lateral projections provided with friction-rollers which engage stationary shoulders which are parallel with the said actuating-shaft, substantially in the manner and for the 125 purpose described.

6. In a power-press substantially such as designated, the combination, with a stationary rotating shaft formed with one or more screw-threads and with one or more toggle-joints, the levers of which are respectively pivotally connected with a stationary part of the apparatus and to a movable platen and with a 130

traveling nut or nuts engaging the said screw or screws upon the actuating shaft, of an anvil or pressure - surface, consisting of a screw which engages a female screw formed in a stationary part of the apparatus, substantially in the manner and for the purpose described.

7. In a power-press substantially such as designated, the combination, with a stationary revolving shaft formed with one or more screw-threads and with one or more toggle-joints, the levers of which are respectively pivotally connected with a stationary part of the apparatus and to a movable platen, and

with a traveling nut or nuts engaging the said screw or screws upon the said actuating-shaft and with an adjustable anvil or pressure-surface, of a stationary indicator-point and a gage upon the said adjustable anvil for regulating and indicating the position of the said pressure-surface with relation to the said movable platen, substantially in the manner and for the purpose described.

JOHN STEWART.
